No. 773,682.

PATENTED NOV. 1, 1904.

V. C. SEVERANCE.
CARBURETER.
APPLICATION FILED MAY 4, 1904.

NO MODEL.

UNITED STATES PATENT OFFICE.

VERNE C. SEVERANCE, OF CHICAGO, ILLINOIS, ASSIGNOR TO PEOPLES INDIVIDUAL GAS COMPANY, OF CHICAGO, ILLINOIS, A CORPORATION OF THE DISTRICT OF COLUMBIA.

CARBURETER.

SPECIFICATION forming part of Letters Patent No. 773,682, dated November 1, 1904.

Application filed May 4, 1904. Serial No. 206,269. (No model.)

To all whom it may concern:

Be it known that I, VERNE C. SEVERANCE, a citizen of the United States of America, residing at Chicago, in the county of Cook and State 5 of Illinois, have invented certain new and useful Improvements in Carbureters, of which the following is a specification.

My invention relates to certain new and useful improvements in carbureters; and its 10 object is to produce a device of this class which shall have certain advantages which will appear more fully and at large in the course of this specification.

To this end my invention consists in certain 15 novel features which are shown in the accompanying drawings and described herein.

In the aforesaid drawings, Figure 1 is a section through a gas-machine fitted with my improved carbureter, the line of the section 20 being indicated by the line 1 1 of Fig. 2. Fig. 2 is a horizontal section in the line 2 2 of Fig. 1. Fig. 3 is a longitudinal section in the line 3 3 of Fig. 1 through the carbureter. Fig. 4 is a perspective view of the carbureter 25 inverted, the bottom plate and wicks being removed; and Fig. 5 is a perspective view of one of the wicks and frame for supporting the same.

Referring to the drawings, it will be seen 30 that the base of my improved carbureter consists of a flat plate of metal A. Upon this plate is mounted a frame B. (Shown inverted in Fig. 4.) This frame is in the form of a hollow box open at the bottom and is provided with a plurality of longitudinally-extending partitions B' B², terminating a short distance above the bottom of the carbureter. These partitions are preferably cast integral with the frame and divide the space within 35 40 the same into a plurality of longitudinal passages. The partitions B' are perforated at one end, and the partitions B² are perforated at the opposite end, so that a tortuous passage is provided through the entire series of longitudinal passages, as indicated by the arrows in Fig. 4.

The partitions B' B² and the outer walls of the frame B, adjacent thereto, are provided

with vertical guides each, consisting of two vertical ribs b, cast integral with the walls and partitions, as illustrated, and in these guides are placed hollow rectangular frames C, over each of which are stretched two sheets of cloth or other absorbent material adapted to serve as wicks.

An inlet-pipe D opens into the hollow frame B at one end of the tortuous passage described and connects the carbureter with a suitable air-pump E, driven by any desired mechanism. At the opposite end of the tortuous passage from the inlet-pipe is a chamber F, closed at the top and bottom and preferably cast integral with the frame B. This chamber, which is best seen in Fig. 3, is provided with an inlet-pipe f, opening into the hollow of the frame. I prefer to cast this pipe into the frame, supporting it in the core which forms the hollow of the chamber F. An exhaust-pipe f' leads out of this chamber and conducts away the gas formed in the carbureter. Two valves f² are provided by which water may be introduced into and removed from the chamber F, the level of the water being maintained above the lower end of the pipe f.

When the frame B is placed in position on the base A, a hollow box having a tortuous passage intercepted by a plurality of absorbent wicks is formed, the partitions being supported a short distance above the base of the carbureter.

When the structure is assembled, a volatile liquid hydrocarbon can be placed in the carbureter through a filling-pipe B³, the level of the liquid being above the level of the lower ends of the wicks and longitudinal partitions. If air is then pumped through the device, it will pass through the tortuous passage and through the wicks, volatilizing the hydrocarbon and forming a combustible gas. The gas will then pass through the chamber F, bubbling up through water therein and being purified thereby. The gas will then pass out through the outlet-pipe f' and can be distributed in any desirable way. The outlet-pipe f' connects with the air-pump E through a

pipe f^2 , in which is a valve f^3 . By this means air from the pump can be mixed with the gas coming from the carburetor to rarefy the mixture, if necessary.

5 I realize that considerable variation is possible in the details of this construction without departing from the spirit of the invention, and I therefore do not intend to limit myself to the details herein shown and described.

10 I claim as new and desire to secure by Letters Patent—

1. In a device of the class described, the combination with a suitable base-plate, of a hollow rectangular frame closed at the top and open 15 at the bottom, mounted upon said base-plate, longitudinal partitions within said frame and integral therewith, terminating above the level of the base-plate, integral ribs on said partitions, frames supported by said ribs and wicks 20 stretched over said frames.

2. In a device of the class described, the combination with a suitable base-plate, of a hollow rectangular frame closed at the top and open at the bottom, mounted upon said base-plate, 25 a plurality of partitions forming a tortuous passage through said frame, walls integral with the frame inclosing a hollow chamber, an

outlet-pipe leading from the upper part of said chamber and a pipe leading from the tortuous passage into the upper portion of said chamber, said pipe being turned down and terminating in the lower portion of said chamber. 30

3. In a device of the class described, the combination with a base-plate, of a hollow rectangular frame closed at the top and open at the 35 bottom, mounted upon said base-plate, a plurality of partitions forming a tortuous passage through said frame, walls integral with the frame inclosing a hollow chamber, an outlet-pipe leading from the upper part of said 40 chamber and a pipe cast into said walls leading from the tortuous passage into the upper portion of said chamber, said pipe being turned down and terminating in the lower portion of 45 said chamber.

In witness whereof I have signed the above application for Letters Patent, at Chicago, in the county of Cook and State of Illinois, this 2d day of May, A. D. 1904.

VERNE C. SEVERANCE.
